UNITED STATES PATENT OFFICE.

JOSEPH ALBERT COOMES, OF LONDON, ENGLAND, ASSIGNOR TO J. A. COOMES & COMPANY LIMITED, OF LONDON, ENGLAND, A BRITISH LIMITED LIABILITY COMPANY.

SPEEDOMETER.

Application filed December 22, 1920. Serial No. 432,437.

To all whom it may concern:

Be it known that I, JOSEPH ALBERT COOMES, subject of the King of England, residing at London, England, have invented 5 certain new and useful Improvements in Speedometers, of which the following is a specification.

This invention is for improvements in or relating to speedometers of the type wherein 10 a propeller-fan is driven from a moving part of the motor vehicle or other apparatus whose speed is to be ascertained, and an indicator-fan is placed in the current of air established by the propeller-fan so that it is 15 angularly displaced about its axis of rotation by the said current, and the degree of such angular displacement is in proportion to the speed of movement of the part whereby the propeller-fan is driven. This type of 20 speedometer further comprises an enclosing casing for the two fans and a separating partition in the form of a sleeve, which is smaller in diameter than the casing and has the propeller-fan set at one open end and the 25 indicator-fan at the other open end, and the air is made to travel through the partitioning sleeve in one direction and outside of it in the other direction between the exterior 30 surface of the sleeve and the surrounding casing.

In speedometers of this type, it has heretofore been the practice to make the separating partition cylindrical in form, and the diameter of the two fans to be approximately 35 equal to that of the interior diameter of the cylindrical sleeve; moreover, the propeller-fan has been made to drive the air through the sleeve.

According to the present invention a 40 speedometer of the type described has the propeller-fan and the indicator-fan separated by a partition which is smaller at the propeller-fan end that it is at the indicator-fan end, and the blades of the propeller-fan 45 are made to extend beyond the circumference of the propeller-fan end of the separator and are arranged to direct the air away from the separator towards the end of the enclosing casing.

50 The invention is illustrated by way of example in the accompanying drawings, wherein:

Figure 1 is a central vertical section show-

ing one form of speedometer according to the invention, and

55 Figure 2 is a partial section through the same taken in a plane at right-angles to Fig. 1.

Like reference letters designate like parts throughout both views.

60 The instrument comprises a cylindrical casing A in which all the parts are enclosed, and a clip A¹ is attached to the casing for securing the instrument to a support. Entering the casing through a boss A² is a spindle B which can be attached in any desired manner to a flexible or other shaft arranged to move with the part whose speed is to be measured, such as a pinion driven by a toothed-wheel on the road-wheel of a motor- 65 vehicle. The spindle B carries fast on it a toothed-wheel B¹ and this meshes with a pinion C which is mounted freely on a fixed stud C¹. Fast on the pinion is an impeller or propeller-fan D, and secured to this is a 70 partition or separator D¹. The separator comprises a sleeve in the form of a hollow truncated cone.

75 The propeller is driven in the direction indicated by the arrow on the partition D¹ and the blades are so placed that when driven in this direction they drive the air towards the back of the casing away from the partition. A spindle E mounted at the front end in a bracket E¹ and at the back 80 end in the stud C¹, carries an indicator-fan-wheel F. This fan-wheel is mounted within the partition D¹ and approximately fills the interior of the same, but the blades project forwardly from the partition an 85 amount that is approximately 25% of the depth of the blades, and such forwardly projecting part has a wider sweep than that which lies within the partition. As shown in the drawing, the amount which these 90 blades project forward is approximately 25% of the total depth of the fan-wheel blades. These blades are set so that they 95 tend to turn the spindle E clockwise as viewed from the front when an air current is made to impinge on the front of the fan-wheel.

The operation of this apparatus is as follows:—

100 The propeller-fan D rotating in the direction indicated by the arrow on the par-

tion D^1 establishes a current of air which moves towards the back of the casing A and is deflected therefrom round the exterior of the partition D^1 to the front of the casing. 5 Here it is again deflected and returns through the partition D^1 and in so doing angularly deflects the indicator-fan F about its axis of rotation, or about the axis of rotation of its spindle E . This spindle is 10 controlled by a spring K in known manner, and thus the angular displacement will be greater or less according to the degree of thrust of the air-current.

The spindle E carries the usual indicator-pointer G which moves over a dial G^1 graduated to show the speed indicated.

The drum H is an ordinary mileage-counter driven by a spindle H^1 which receives its motion from a pinion not shown in the 20 drawing but which meshes with the wheel B^1 .

What I claim as my invention and desire to secure by Letters Patent is:—

1. In a speedometer, the combination with 25 a case, of a sleeve mounted coaxially therein with a free annular space provided between its periphery and the case, which sleeve is of such form that it presents a plain exterior surface, an impeller of larger 30 diameter than the sleeve mounted coaxially in the case at one end of the sleeve with a free annular space between the periphery of the impeller and the case, the blades of 35 the impeller having parts thereof operative for moving the air through the sleeve in a direction towards it, extending partly across the adjacent open end of the sleeve, a spring-controlled indicator fan-wheel mounted coaxially with the impeller at the 40 other end of the sleeve, and means for rotating the said impeller in such a direction as to draw the air through the fan-wheel and through the sleeve and drive it against the adjacent end of the case away from the 45 sleeve, for the purpose specified.

2. In a speedometer, the combination with 50 a case, of a sleeve mounted coaxially therein with a free annular space provided between its periphery and the case, which sleeve is of such form that it presents a plain exterior surface, an impeller of larger diameter than the sleeve mounted coaxially in the case at one end of the sleeve with a free space between the periphery of the impeller and the 55 case, the blades of the impeller having parts thereof operative for moving the air through the sleeve in a direction towards it, extending partly across the adjacent open end of the sleeve, a spring-controlled indicator fan-wheel having blades of the screw-propeller type mounted coaxially with the impeller at the other end of the sleeve, which blades project forward of the sleeve an amount that 60 is approximately 25% of the total depth of the fan-wheel blades, and means for rotat-

ing said impeller in such a direction as to draw the air through the fan-wheel and through the sleeve and drive it against the adjacent end of the case away from the sleeve for the purpose specified.

3. In a speedometer, the combination with 70 a case, of a sleeve in the form of a truncated cone mounted coaxially therein with a free annular space provided between its periphery and the case, which sleeve is of such 75 form that it presents a plain exterior surface, an impeller of larger diameter than the sleeve mounted coaxially in the case at one end of the sleeve with a free space between the periphery of the impeller and the case, the blades of the impeller having parts thereof operative for moving the air through the sleeve in a direction towards it, extending partly across the adjacent open end of the sleeve, a spring-controlled indicator fan-wheel mounted coaxially with the impeller at the other end of the sleeve, and means for rotating the impeller in such a direction as to draw the air through the fan-wheel and through the sleeve and drive it 80 against the adjacent end of the case away from the sleeve, for the purpose specified.

4. A speedometer, comprising, in combination, a cylindrical case, an impeller mounted coaxially in the rear of said case, a sleeve in the form of a truncated cone carried coaxially by its smaller end on the front of said impeller, a free annular space being provided between the inner periphery of said case and the impeller and said sleeve, 100 a spring-controlled fan-wheel mounted coaxially in the larger end of said sleeve, an indicator operatively connected with said fan-wheel, and means for rotating said impeller so as to drive the air against the back wall of the case away from the sleeve, an unobstructed passage being provided for a steady current of air from the back of the case, outside the sleeve, through the fan-wheel to the middle of the impeller.

5. In a speedometer, the combination with 110 a cylindrical case, of a sleeve in the form of a truncated cone mounted coaxially therein with a free annular space provided between its periphery and the case, the smaller end of said sleeve being located at the rear end 115 of the case, which sleeve is of such form that it presents a plain exterior surface, an impeller of larger diameter than the sleeve mounted coaxially in the case at the rear end of the sleeve with a free space between the periphery of the impeller and the case, the blades of said impeller having parts thereof operative for moving the air through the sleeve in a direction towards it, extending partly across the adjacent open end of the sleeve, a spring-controlled indicator fan-wheel mounted coaxially with the impeller at the front end of the sleeve, the blades of 120 which fan-wheel project forward of the 125 sleeve, and means for rotating the impeller at the front end of the sleeve, the blades of which fan-wheel project forward of the 130

sleeve an amount that is approximately 25% of the total depth of the fan-wheel blades, and means for rotating said impeller in such a direction as to draw the air through the 5 fan-wheel and through the sleeve and drive it against the adjacent end of the case away from the sleeve, for the purpose specified.

6. In a speedometer, the combination with a case, of a sleeve having an unobstructed 10 throughway mounted coaxially therein with a free annular space provided between its periphery and the case, which sleeve is of such form that it presents a plain imperforate exterior surface, an impeller of larger 15 diameter than the sleeve mounted coaxially in the case at one end of the sleeve with a free annular space between the periphery of the impeller and the case, the blades of the impeller having parts thereof operative for

moving the air through the sleeve in a direction towards it, extending partly across the adjacent open end of the sleeve, a spring-controlled indicator fan-wheel mounted coaxially with the impeller at the other end of the sleeve, and means for rotating the 25 said impeller in such a direction as to draw the air through the fan-wheel and through the sleeve and drive it against the adjacent end of the case away from the sleeve, for the purpose specified. 30

In testimony whereof I have signed my name to this specification in the presence of two subscribing witnesses.

JOSEPH ALBERT COOMES.
